PLATE

Clarence Le Roy Witmer, Lansdale, Pa., assignor to
American Can Company, New York, N.Y., a corpora-
tion of New Jersey

Filed Sept. 12, 1961, Ser. No. 66,702

Term of patent 14 years

(Cl. D44—15)

Fig. 1

Fig. 2

*Fig. 3**Fig. 4*FIG. 1 is a plan view of a plate of conventional configuration showing my new design, the motif of the rim continuing about the entire periphery thereof;

FIG. 2 is an enlarged fragmentary view of the plate shown in FIG. 1;

FIG. 3 is an enlarged sectional view taken substantially along line 3-3 of FIG. 2; and

FIG. 4 is an enlarged sectional view taken substantially along line 4-4 of FIG. 2.

My design is characterized by a plate having a central bowl portion and a surrounding rim terminating in a skirt, said rim having contiguous circumferential or peripheral lines of substantially rectangular, regularly shaped, equally spaced embossments, with the embossments in one line, when taken in a radial direction, being staggered and in contact with the contiguous emboss-

ments in a contiguous line. The design is further characterized by having the embossments in the outermost line merge with said skirt, and the embossments in the innermost line arranged closely adjacent the juncture of said rim and said bowl portion.

I claim:

The ornamental design for a plate, substantially as shown and described.
